FOREIGN PATENT DOCUMENTS

WO 2008146964 A1 12/2008

Primary Examiner — Darlington Ly

(74) *Attorney, Agent, or Firm* — Cooley LLP; Nathan W. Poulsen

(57) **CLAIM**

The ornamental design for a display apparatus, as shown and described.

DESCRIPTION

FIG. 1 is a front and bottom perspective view of the display apparatus showing my new design;

FIG. 2 is a front and side perspective view thereof;

FIG. 3 is a top plan view thereof;

FIG. 4 is a front and bottom perspective view of the display apparatus in accordance to an alternate embodiment;

FIG. 5 is a front and side perspective view thereof; and,
FIG. 6 is a top plan view thereof.

The broken lines of “dash-dot-dot” form appearing in FIGS. 4-6 represent a symbolic break in which the appearance of any portion of the article between the break lines forms no part of the claimed design.

1 Claim, 6 Drawing Sheets
